W. HOWE.

Nurse Lamp.

Patented Dec. 31, 1812.

William Howe.

1862 X

Sitter's Patent.

The Schedule referred to in these Sitter's Patent and
making part of the same, containing a description in the wording
of the said William Howe, himself of his invention call'd these Lamps.

The invention of this improvement in Lamps call'd the
"Improved House Lamp" consists in constituting the lamp body
with an eclipsor or shadow to obstruct the light entirely as
seen in any direction and with a tinder box at the bottom and
the handle of the lamp to make a stove, the upper part of it
serving as a temperary candle stick or a convenience which is often
wanted; and also containing the requisite construction for the purpose
of warming drink or food in the liquid state during the night.
This lamp is made of sheet tin in shape like a common lantern
and neither smaller in size or larger as may be wanted. The handle
box is fitted on the bottom of the lamp, which serves as a stove body.
The eclipsor is a cylinder part in the inside of the lamp having half
of its tube cut out, so that when the open place is turned to the open
place at the bottom of the lamp the light then will shine into the room.
and when the said eclipsor is turned round it obstructs the light.
To the top of this eclipsor is attached the top of the lamp made somewhat
like the top of a lantern and by which the eclipsor is turned round or taken
out. To the bottom of said eclipsor is fix'd a circle on which it turns.
The lamp for the oil and light is a small vessel placed inside of said
eclipsor, having a circle of tin part in the bottom of the body of the
lamp, or lantern part to keep it steady and in its place. Proper
receptacles are made in the sides of top of the lamp and shaded
with blinds in such a manner as to prevent the light from shining
into the room when the light is extinguish'd. The open place cut out of the eclipsor
and through which the light is admitted into the room, may be covered
from

from the air, by putting in a piece of slate, commonly called iron glass, the upper vessel in which drink is to be warmed, are fitted into the top of the lamp, and when used, the said coliphor is taken out and the said upper vessel is heated from the lamp under it till warm, it is as it might be wanted. The handle of the lamp has a perpendicular tube with a lid on its top. This tube may be used as a temporary candle stick for which it is designed. At the back side where the said handle is placed, several holes are cut through the iron for the purpose of letting in air to supply the fire of the lamp. These holes do not extend up higher than the circle on the bottom of the chimney, which said circle prevents the light from shining through the said air holes. It is best to have the lamp, when said coliphor is finished with iron glass as before mentioned said lamp may be used as a lantern as then the light will be secured from the wind and be rendered safe.
